ATTORNEY

UNITED STATES PATENT OFFICE.

ALEXANDER HARRIS, OF NEWARK, NEW JERSEY, ASSIGNEE TO LOUIS V. ARONSON,
OF NEWARK, NEW JERSEY.

IGNITER.

Application filed March 2, 1921, Serial No. 449,107.

To all whom it may concern:

Be it known that I, ALEXANDER HARRIS, a citizen of the United States, residing in the city of Newark, county of Essex, and State of New Jersey, have invented certain new and useful Improvements in Igniters, of which the following is a full, clear, and exact description, such as will enable others skilled in the art to which it pertains to make, construct, and use the same, reference being had to the accompanying drawings, and to the numerals of reference marked thereon, forming a part of this specification.

My invention relates to that class of igniters in which a wire is employed, bent in such a manner as to provide a convenient handle for operating the device, one end of said wire being provided with a scratching element secured to it in any desired or convenient manner, and the other end of which has secured thereto a spark producing element.

The object of this invention is to provide adjustable means in which the spark producing element is located, which at all times will keep it in frictional engagement with the scratching element, until it is entirely used up.

In carrying out my invention, I make use of the structures illustrated in the accompanying drawings, wherein—

Figure 1 represents, a plan view of my improved device.

Figure 2 represents, on an enlarged scale the tubular member, in section, secured to one end of the wire handle, the spark producing element being removed therefrom.

Figure 3 represents, a similar view with the spark producing element located therein, and pressing against the scratching element illustrated in dotted lines.

Figure 4 represents, a slightly modified form of my invention, in which the tubular member is illustrated as having screw threaded engagement with the screw threaded end of the wire handle; and

Figure 5 represents, a plan view of the structure illustrated in Figure 3.

Similar numerals of reference refer to like parts throughout the specification and drawings.

In the drawings referred to a spring wire is bent, preferably into the shape illustrated in the drawings, to provide a convenient handle 1 for operating the device.

Secured to one end of the wire, in any desired or convenient manner, is a scratching element 2, preferably made from a steel rod or bar rectangular in cross section provided upon one face thereof with a suitable number of serrations or teeth 3, whereby a scratching member or element is produced.

Revolvably secured to the other end of the wire is a tubular member 4, provided with a centrally arranged bore 5 terminating in an enlarged cavity 6. The tubular member 4 is secured to the end of the wire by offsetting the end thereof as clearly indicated at 7, thereby preventing accidental separation of the same.

Located in the cavity 6 is a spark producing element or metal 8 consisting of preferably cerium and iron.

Pressing the end of the wire to which the tubular member 4, containing the spark producing element is secured, in the direction indicated by the arrow, said spark producing element is caused to rub against the serrated face of the scratching element by means of the construction of the handle, thereby causing a shower of sparks to be emitted from the lighter.

The tubular member 4 containing the spark producing element 8 may be provided with an exteriorly knurled surface if so desired.

The cavity 6 of the tubular member 4 is approximately of the same diameter as the spark producing element 8 in order that it may be frictionally held therein. The centrally arranged bore 5 which communicates with the cavity 6 is slightly larger in diameter than the wire to which it is secured so that it is freely movable thereon.

In the construction shown in Figure 4 the end of the wire is screw threaded as at 9 and the centrally arranged bore is similarly screw-threaded so that the tubular member 4 can be adjusted thereon.

It will thus be seen that this construction enables the spark producing element to be entirely used up, due to the fact that the headed end 7 of the wire tends to constantly press the spark producing element 8 against the teeth of the scratching element.

Hitherto in the construction of similar devices, a tubular element having a uniform bore was rigidly secured to the end of the wire and a piece of spark producing element was rigidly secured in the other end.

This resulted in a considerable waste of the spark producing element, inasmuch as that portion of the spark producing element which was secured in the tubular member could not be utilized.

Experience has demonstrated that the organization above described is a highly efficient one, and while I have shown the preferred embodiment of my present invention, 10 I do not wish to be limited to the exact details of construction shown and described, as obvious modifications thereof, not involving the exercise of invention, may be made by any skilled mechanic, and such departures from what is herein set forth, I consider within the scope and terms of my 15 claims.

Having thus described my invention, what I desire to secure by Letters Patent is:—
20 1. An igniter of the class described, comprising a handle made from a single piece of suitable material, a scratching element secured to one end of the handle, a tubular member slidably disposed upon the other 25 end of said handle, said tubular member provided with a cavity, and a spark pro-

ducing element frictionally located within said cavity designed to be pressed against said scratching element by the end of said handle.

30

2. An igniter of the class described, comprising a handle made from a single piece of wire, a scratching element secured to one end of said wire, a tubular member slidably disposed upon the other end of said wire, 35 said tubular member provided with a centrally arranged bore terminating in an enlarged cavity, the end of said wire extending into said cavity and being offset, a spark producing element frictionally located within said cavity, one end of which is in engagement with and operatively adjusted by the offset portion of the wire and the other end of which is adapted to press against the said scratching element.
